UNITED STATES PATENT OFFICE.

SIGVALD DAHL, OF MYRVALL PR. OSLO, NORWAY, ASSIGNOR OF ONE-HALF TO
HAROLD CARLSEN, OF BROOKLYN, NEW YORK.

SAFETY DEVICE FOR BURNERS.

Application filed April 8, 1925. Serial No. 21,564.

This invention relates to an appliance adapted to prevent the removal of a burner while fuel is flowing through the same. While not limited thereto the device is particularly useful in connection with oil burners such as used for supplying fuel to marine boilers.

It is known to those skilled in the art that the burners of marine boilers are frequently removed for the purpose of cleaning or making repairs due to parts of the burner being destroyed or rendered inefficient by the excessive heat in the boiler. On shipboard it is frequently necessary to remove the burners several times per hour. The removal of the burners is a constant source of danger to those operating them because if through carelessness or lack of knowledge on the subject the burner is removed without first closing the valve which supplies fuel thereto the hot fuel will be discharged into the boiler room. The fuel oil used for most boilers is supplied under a high pressure and is frequently preheated to a high temperature and many accidents have occurred on shipboard due to the removal of the burners without first cutting off the oil supply.

My invention aims to provide means which will prevent the removal of the burner as long as fuel is flowing thereto but will permit such removal after the fuel supply has been cut off. An embodiment of the invention is illustrated in the accompanying drawings in which—

Fig. 1 is a sectional view showing a burner and related parts provided with my improved safety device;

Fig. 2 is a vertical section on line 2—2 of Fig. 1;

Fig. 3 is a section on line 3—3 of Fig. 1;

Fig. 4 is a view similar to Fig. 3 but showing the safety device in the position it takes after the fuel control valve is closed;

Fig. 5 is a horizontal section on line 5—5 of Fig. 3;

Fig. 6 is a perspective detail view illustrating part of the mechanism shown at the right in Fig. 5.

Referring in detail to the drawings, 10 represents a boiler front having an opening 12 therein through which projects a nozzle 14 of a known type of burner conventionally shown in Fig. 1 and indicated as a whole by 55 the numeral 15. This burner has a duct 16

formed therein. The inlet 18 of this duct terminates at a seat 20 formed on the burner which is adapted to engage a mating seat 22 formed on the end of a fixture 24 which is rigidly secured to the boiler front in any suitable manner, for example, as indicated by screws 26. The fixture 24 has a duct 28 therein which registers with the duct 18 in the burner. The duct 28 is connected by means of pipe 30 and union 32 with a globe valve 34 which controls the passage of oil or other fuel from the pipe 36. The latter pipe is connected with a suitable source of supply and the fuel is adapted to be fed to the burner under pressure according to the usual practice.

As illustrated in Fig. 1, the plug 38 of the valve is retracted from its seat, hence, the fuel is free to flow from the pipe 36 to the pipe 30 and through the ducts 28 and 16 and thence to the interior of the boiler.

Means are provided for detachably securing the burner 15 to the fixture 24 and a safety device is associated with the holding means in such a manner that the burner cannot be removed unless the control valve 34 is closed. This means includes a yoke-like member 40 which is pivoted on a suitable stud 42 secured to the fixture 24. The outer end of the yoke member 40 has a hub 44 formed thereon through which is threaded a clamp screw 46 having a bevelled end 48 adapted to engage a conical seat 50 formed in the burner. The outer end of the clamp screw is formed with a square head 52 so as to afford a good purchase for a wrench or other tool for manipulating the screw. When the valve 34 is in open position as shown in Fig. 1, access to or manipulation of the head 52 of the clamp screw is prevented by means of a guard portion 54 carried by a member 56 which is loosely pivoted on a shaft 58 journalled in suitable brackets 60 and 62 extending outwardly from a base plate 64 secured by means of screws 66 to the boiler front. The member 56 has a hub portion which is formed with a tooth 68. A latch 70 pivoted at 72 to a lug 74 formed on the base plate normally engages the tooth 68 and holds the guard member in the position shown in Figs. 1 and 3. The shaft 58 has rigidly secured thereto an arm 76 which carries at its outer end a pin 78 adapted at the proper time to strike the underside of the latch 70 so as to release the member 56.

105
100
110

The shaft 58 is operatively connected with the valve stem 80 of the valve 34 by means of a system of links and levers in such a way that when the valve stem is turned in a direction to close the same, at the end of the closing movement the shaft 58 will have been rocked through a sufficient distance to bring the pin 78 into position to trip the latch 70 and thus cause the guard 54 to drop and permit access to the clamp screw 52. This released position is shown in Fig. 4. The linkage for accomplishing the above includes a crank arm 82 carried on one end of the shaft 58 which is connected by means of a link 84 to the lower end of a lever 86 pivoted at 88 to a suitable bracket 90. The upper end of the link 86 is pivotally secured to a link 92 which in turn is connected to a vertically extending link 94 having an eye 96 formed in its upper end through which the valve stem 80 projects. Collars 98 and 100 are secured on opposite sides of the link 94 so that as the hand wheel 102 of the valve is turned the motion thereof will be transmitted through the linkage described to the rock shaft 58. As above mentioned, when the valve is in closed position the guard member 56 will be in the position shown in Fig. 4, hence, the operator can unfasten the clamp screw 46 so as to remove the burner from the furnace for the purpose of cleaning or renewing parts. And this act will be unaccompanied by danger to the operator as no fuel can flow from the duct 28 while the valve is closed.

After the burner has been cleaned or repaired it is again put in position indicated in Fig. 1 and the clamp screw tightened up so as to seat the surfaces 20 and 22 firmly against one another. The operator then turns the valve stem in the proper direction to open the valve. This action rocks the shaft 58 in the direction of the arrow α indicated in Fig. 4. During this turning movement the member 56 is caused to partake of the turning movement of the shaft because of the engagement of a shoulder 104 formed in a collar 106 secured to the shaft, with a projection 108 extending longitudinally from the hub portion of the member 56. When the valve reaches its fully opened position, the guard portion 54 of the member 56 encloses the end of the clamp screw and the latch 70 will drop into the position shown in Fig. 3 so as to hold the parts in the position shown until the valve is again closed.

From the above it is apparent my invention provides means which makes the insertion and removal of fuel burners practically foolproof. By its use the safety of workmen is insured and fire hazard is greatly diminished. The embodiment of the invention illustrated and described corresponds to an installation, the utility of which has been demonstrated on board ship. It is not to be construed, however, that the invention is limited to use on oil burners and it will be appreciated that it can be readily adapted for use in connection with other types of apparatus.

While I have described with great particularity the embodiment of the invention illustrated, it is not to be construed that I am limited thereto as modifications and substitution of equivalents may be made by those skilled in the art without departing from the invention as defined in the appended claims.

What I claim is:

1. In combination with a burner, a pipe for supplying fuel thereto, means for detachably holding the burner in communication with said pipe, a valve in said pipe having a movable valve stem, a shaft arranged to be actuated by said valve stem, a member loosely pivoted on said shaft and having a guard portion, a latch for normally holding said member in such position that the guard portion prevents manipulation of said holding means and means for tripping said latch upon the completion of the closing movement of said valve stem.

2. In combination with a marine boiler, an oil burner and a pipe for supplying oil thereto, a fixture secured to the boiler front and having an inlet passage connected with said pipe and an outlet passage communicating with said burner, a manually operable clamp adapted to firmly seat the burner against said fixture, a valve controlling the flow of oil through said pipe, a shaft arranged to be rocked in opposite directions upon the opening and closing of said valve, a member loosely pivoted on said shaft and having a portion normally preventing movement of said clamp, a latch engaging said pivoted member, and means movable with said shaft for tripping said latch.

In witness whereof, I have hereunto signed my name.

SIGVALD DAHL.
